UNITED STATES PATENT OFFICE.

DAVID S. JACOBUS, OF JERSEY CITY, NEW JERSEY, ASSIGNOR TO THE BARCOCK & WILCOX COMPANY, OF BAYONNE, NEW JERSEY, A CORPORATION OF NEW JERSEY.

STEAM BOILER AND FURNACE THEREFOR.

Original application filed July 2, 1918, Serial No. 242,990. Divided and this application filed December 22, 1920. Serial No. 246,350.

To all whom it may concern:

Be it known that I, DAVID S. JACOBUS, a citizen of the United States, residing in Jersey City, in the county of Hudson and State of New Jersey, have invented certain new and useful Improvements in Steam Boilers and Furnaces Therefor, of which the following is a full, clear, and exact description, reference being had to the accompanying drawing, forming part of this specification, the drawing being a sectional side elevation of a horizontal water tube boiler constructed in accordance with my invention.

15 The present application is a division of my application Serial No. 242,990, which was filed in the United States Patent Office July 2, 1918, Patent No. 1,470,744, Oct. 16, 1923, and relates particularly to furnace structure 20 which co-operates with a boiler of the character described and claimed in the parent application.

In the drawing, 2 represents an upper bank of horizontally inclined tubes, and 3 a corresponding lower bank, shown as comprising three rows, the two banks of tubes preferably being separated a distance corresponding to the width of a plurality of rows. The front and rear furnace walls are 25 indicated by the reference numerals 40 and 41, respectively, both walls being inclined outwardly on both their inner and outer faces, and the inner wall being inclined from a point adjacent the stoker ledge plates, 30 the furnace lining preferably being substantially all of refractory material. The front wall is supported by a member 40^a, the rear wall 41 being provided with an opening 41^a affording access to the stoker and through 35 which a tool may be inserted to remove the clinker which collects over the stoker dump plates. The combustion chamber 4, below the lower set of tubes, extends substantially the entire length of the tubes and is of a 40 hopper-shaped construction, with the underfeed stoker 5 at the narrow part of the hopper, the front of the underfeed stoker 5 coming under the uptake headers 6.

The lower ends of the upper bank of 45 water tubes enter a group of headers 7, while the lower ends of the lower tubes 3 enter headers 8, these headers 7 and 8 being connected by long spaced-apart nipples 9. A baffle 10, disposed at the rear of the boiler,

extends over the upper row of tubes 3 from the headers 8 for a portion of their length, and from the inner end of this baffle a vertical baffle extends upwardly, being formed in part as the baffle 11 between the rows of tubes of the upper bank, and in part of superheater headers 12, 12^a, 12^b and 12^c, and portions of baffling between them. In the form shown, the superheaters are provided with U-tubes 13, whose ends are connected to the headers. It will be noted that the upwardly projecting part of this baffle, extending through the bank, is at an angle to the planes of the headers, such that the upward flow space is gradually contracted as the gases rise through the tubes after flowing along substantially the entire length of the lowermost tubes.

The steam from the steam and water drum 14 passes through pipe 15 to the header 12, thence through the U-tubes to the header 12^a, whence it flows through nipples into header 12^b, and thence through the longer U-tubes to the upper header 12^c, where it is taken off. The gases rise from the furnace through the lower group of tubes, pass up to the left of the baffles until they rise through the upper group of tubes, and then flow down through the upper group of tubes and out between the nipples 9 to the offtake flue 16.

In my prior application, above referred to, is shown a two-stage economizer comprising a high-pressure stage and a low-pressure stage. In my present application, the low-pressure stage is omitted and a portion only of the high-pressure stage of the economizer is shown at A, the waste gases from the boiler flowing downwardly over the high-pressure stage. The economizer construction may be the same as that shown in my Patent No. 1,281,016, which was issued October 8, 1918.

The advantages derived through the form of combustion chamber shown, where the gases produced through combustion flow through progressively increasing areas in traveling through the furnace from the fuel bed to the boiler tubes and contact with substantially the full length of the lowermost tubes, are that the gases are made to impinge against the lowermost boiler tubes in a reasonably uniform way throughout their length, thus distributing the heat from end to end of the tubes and avoiding local

intensification of action at certain points through a torch-like effect of the flames. After distributing the gases by means of the special form of furnace, so that they contact with the entire length of the lowermost tubes, the gases are directed forwardly by the roof baffle and are made to flow into the lower part of the first pass, after which they flow through progressively decreasing areas throughout the boiler, thus imparting a maximum amount of heat to the boiler with a minimum draft drop.

The arrangement is particularly adaptable to an underfeed stoker where excess air, under certain conditions of operation, passes through the rear part of the stoker mechanism, and through the dumping plates, and is projected rearwardly in the furnace. The form of the tuyères of the stoker, which admit the compressed air, causes the air to be projected rearwardly, and when the rear portion of the fire becomes thin, or when a portion of the fire is broken through by the action of the blast, the construction of the tuyères is such as to project the air and gases rearward. It can be readily seen that where a stoker produces an action of this sort, the form of furnace is particularly adapted to give increased efficiency over an arrangement wherein the excess air and gases, projected to the rear of the furnace, would pass directly upward along the rear wall of the furnace and enter the spaces between the boiler tubes without being mingled with the combustible gases in the interior of the furnace.

Building the front and rear walls of the setting so as to make them incline outwardly, as shown, the front wall being inclined from a point adjacent the stoker ledge plates, is advantageous in maintaining the brickwork, as the weight of the wall of itself holds the walls in alignment and prevents the walls from bulging inwardly. This element is important in connection with the high capacities at which boilers and furnaces are now being operated.

It is especially desirable in connection with underfeed stokers of the type shown, where the action of the forced blast often causes difficulties through erosion of the front walls. Again, in burning certain coals, clinkers may form in the fire pit, and the top of the fire pit may also cake or become encrusted so as to cause the forced blast to project torch-like flames against the front wall. Inclining the front wall outward at the top, in the way shown, is, therefore, especially advantageous where stokers of the forced blast, underfeed type are employed. Inclining the front wall outward, in the way described, necessitates its being supported in part by the outer member or members arranged to come in front of the wall.

It is especially advantageous in the case of an underfeed stoker, to set the stoker further beneath the boiler than in ordinary practice, and to incline the front wall outwardly in the way described, as, in addition to increasing the mingling effect of the gases and thereby promoting combustion, the erosion of the front wall through the action of the hot gases, which is characteristic of this type of stoker, will be minimized or eliminated. The erosion referred to comes through the impinging action of the hot gases and through the swirling or vortex action of the gases produced through the effect of the forced blast which enters through the tuyères near the front of the furnace and the form of the fuel bed resulting from the underfeed method of supplying the coal, which causes the depth of the fuel bed to be greater a short distance from the front wall than it is directly against and near the front wall. With a vertical front wall, the combustion conditions may be such as to cause a lane of flame and unconsumed gases to pass upwardly along the wall and into the spaces between the boiler tubes before the gases are consumed in the furnace, and, at the same time, there may be difficulty through the erosion of the inner face of the wall through the impinging action of the hot gases, or through the swirling or vortex action. By inclining the front wall outwardly, the difficulties referred to are minimized or entirely overcome. Under the same conditions, the use of a vertical front wall would lead to a lane of flame hugging the wall, while the use of an inclined front wall of the character illustrated herein, would cause the flame to be spread out and broken up through eddy currents before it reached the tubes, with a resulting increase in the amount of combustible gases burned within the furnace chamber. By reducing the swirling and vortex action of the gases through the use of an inclined wall, where the face of the wall will be a greater distance from the point from which the hot gases are projected from the fuel bed than with a vertical wall, the amount of erosion will be greatly decreased over that which would exist with a vertical wall. Inclining the rear wall outwardly also increases the mingling effect of the gases in the case of underfeed stokers, so that the form of furnace described is particularly adaptable to underfeed stokers. These same advantages are embodied in the form of furnace shown in my application Serial No. 302,728, filed June 9, 1919. In the furnace shown and described in connection with the latter application, the front wall of the furnace extends vertically a short distance above the stoker ledge plates and then inclines outwardly, the vertical portion of the wall being protected by the cross box shown in the front.

of the furnace chamber, through which water from the boiler is circulated. It has been found advantageous to incline the front wall outwardly from directly above the stoker ledge plate, as illustrated in the present application. Inclining the front wall outwardly from directly above the stoker ledge plates, as herein shown, reduces to a still further point, the erosive effect of the gases on the inner face of the wall and avoids the necessity of protecting the lower portion of the wall by water-boxes, as is done in the case of my prior application.

The arrangement is particularly useful where particles of fuel or of ash containing combustible matter are thrown upwardly in the furnace, as is the case with a forced-blast underfeed stoker or other types of forced blast stokers, or where any other method of burning coal is used where such particles are carried upwardly by the products of combustion, as the widening effect of the top of the furnace reduces the velocity of the gases, which, in turn, reduces the speed at which the particles are traveling and causes them to remain in suspension a longer time within the furnace, or to spread out and to be whirled in eddies within the furnace, or to fall along the sides of the furnace to the bottom of the furnace. This action gives a longer time for the particles to burn within the furnace and increases the efficiency of combustion. The burning out of the particles within the furnace, combined with the large flow area between the boiler tubes at the bottom of the first pass, reduces the slagging difficulty, so that, in addition to securing a higher efficiency, the combination gives better operating results.

Furthermore, the described furnace construction permits the use of access doors in the inclined wall for a furnace in which practically the entire length of the lowermost tubes are exposed to the radiant heat of the furnace.

With the device illustrated, when the gases pass into the water tubes, they enter what is, in effect, the gas outlet of the furnace, which is directly above the fuel bed; so that the gases pass in a generally vertical direction from the fuel bed. If the fuel bed were close to the water tubes, and hence close to the gas outlet, there would be no chance for the gases to mingle thoroughly and be completely burned before reaching the tubes. Applicant prefers to make the furnace chamber high enough so that the gases will be thoroughly mingled and substantially burned before striking the relatively cold water tubes. This increased height of the furnace introduces a new factor—viz, the swirling or vortex action of the gases which causes erosion of the front wall. To overcome this difficulty and, at the same time, have a relatively high com-

bustion chamber, applicant uniformly inclines the front wall and supports it by a member located in front thereof, thereby, at the same time, minimizing the tendency to erosion and overcoming the tendency of the wall to fall inwardly should erosion take place. Furthermore, inclining the front wall, and preferably also the rear wall to produce a hopper shaped furnace, in itself serves to increase the mingling effect of the gases and helps to bring about the complete burning thereof before reaching the boiler tubes.

By providing the inclined rear wall with an opening adjacent to the dumping bars, it is possible for the operator to stand nearer the dumping bars in removing the clinker than would be the case with a vertical wall built up to the ends of the tubes. The combination, therefore, serves to provide an efficient arrangement for getting at the clinker where a stoker or other grate is set in a position with reference to the boiler similar to that shown in the drawings.

While I have herein shown and described one embodiment of my invention, I do not desire to be limited to the exact arrangement shown and described, but seek to cover, in the appended claims, all those modifications which come within the true spirit and scope of my invention.

What I claim and desire to secure by Letters Patent of the United States is:

1. In combination, a furnace having an unobstructed upwardly increasing flow area, water tubes disposed above the furnace extending in a horizontally inclined direction, the lowermost of the tubes being exposed to the furnace chamber throughout substantially their entire length and said furnace chamber being sufficient in height to permit substantially complete combustion of the gases before reaching said tubes, a horizontally inclined baffle disposed above certain of the tubes, and means for directing the gases in a decreasing flow area in the first pass across the tubes.

2. In combination, a furnace having its front and rear walls upwardly and outwardly inclined to form an unobstructed upwardly increasing flow area in the furnace chamber, water tubes disposed above the furnace extending in a horizontally inclined direction, the lowermost of the tubes being exposed to the furnace chamber throughout substantially their entire length and said furnace chamber being sufficient in height to permit substantially complete combustion of the gases before reaching said tubes, a horizontally inclined baffle disposed above certain of the tubes, and means for directing the gases in a decreasing flow area in the first pass across the tubes.

3. In combination, a furnace having its front and rear walls upwardly and out-

- wardly inclined on both their inner and outer faces to form an unobstructed upwardly increasing flow area in the furnace chamber, water tubes disposed above the furnace extending in a horizontally inclined direction, the lowermost of the tubes being exposed to the furnace chamber throughout substantially their entire length and said furnace chamber being sufficient in height to permit substantially complete combustion of the gases before reaching said tubes, a horizontally inclined baffle disposed above certain of the tubes, and means for directing the gases in a decreasing flow area in the first 15 pass across the tubes.
4. In combination, a forced blast under-feed stoker, the furnace walls forming a hopper-shaped furnace, parallel inclined boiler tubes located above said furnace and comprising at least two banks of tubes spaced apart, a roof baffle located above the lower bank, the tubes of the lower bank being exposed for substantially their entire length, and means comprising a baffle extending upwardly from the end of said roof baffle across the tubes, forming a progressively decreasing flow area for the gases.
5. In combination, a furnace having an unobstructed upwardly enlarging furnace chamber, horizontally inclined water tubes comprising two spaced banks located above the furnace chamber, the lowermost tubes being directly exposed for substantially their entire length to the radiant heat of the furnace, said furnace chamber being sufficiently high to permit approximately complete combustion of the gases before reaching said tubes, a roof baffle located above certain of the tubes and extending longitudinally thereof, and means defining a constricted first pass across the tubes through which the 20 gases flow, said means including said baffle located above certain of the tubes.
6. In combination, a furnace having an unobstructed upwardly enlarging furnace chamber, horizontally inclined water tubes comprising two spaced banks located above the furnace chamber, the lowermost tubes being directly exposed for substantially their entire length to the radiant heat of the furnace, said furnace chamber being sufficiently high to permit approximately complete combustion of the gases before reaching said tubes, a baffle located above certain of the tubes and extending parallel thereto, means defining a constricted first pass across the tubes through which the gases flow, said means including said baffle located above certain of the tubes.
7. In combination, a furnace having an unobstructed upwardly enlarging furnace chamber, fuel feeding mechanism for the furnace which causes heated particles to be carried upwardly through the furnace chamber, substantially parallel horizontally inclined water tubes comprising two spaced banks located above the furnace chamber and spaced apart a distance corresponding to the width of a plurality of rows, the lowermost tubes being directly exposed for substantially their entire length to the radiant heat of the furnace, said furnace chamber being sufficiently high to permit approximately complete combustion of the gases before reaching the 25 boiler tubes, a baffle located above certain of the tubes and extending parallel thereto, and means defining a constricted first pass across the tubes through which the gases flow, said means including said baffle located above certain of the tubes.

DAVID S. JACOBUS.
